UNITED STATES PATENT OFFICE.

DELOS DUNTON AND EDWARD A. HENDRICKS, OF CARPENTERSVILLE, ILLINOIS, ASSIGNEES TO THE STAR MANUFACTURING COMPANY, OF SAME PLACE.

DESIGN FOR A DIE.

SPECIFICATION forming part of Design No. 28,208, dated January 25, 1898.

Application filed December 15, 1897. Serial No. 662,083. Term of patent 14 years.

To all whom it may concern:

Be it known that we, DELOS DUNTON and EDWARD A. HENDRICKS, citizens of the United States, residing at Carpentersville, in the county of Kane and State of Illinois, have invented and produced a new and original Design for Dies, of which the following is a specification, reference being had to the accompanying drawings, forming part thereof, in which—

Figure 1 is a perspective view of our new design, and Fig. 2 is a top plan view thereof.

As shown in the drawings, the leading or material feature of our design consists of a generally Y-shaped figure. This figure comprises substantially a body A, which tapers

down to a point B at its lower end and has upwardly and outwardly divergent wings or extensions C, provided with squared ends D, which are connected with the point B by curved sides E, while their other sides F are straight and meet each other at an angle G.

Having thus fully described our invention, what we claim, and desire to secure by Letters Patent, is—

The design for a die, substantially as herein shown and described.

DELOS DUNTON.

EDWARD A. HENDRICKS.
